POTATO CUTTING TABLE AND TREATER

Roy A. Hurtt, Hoople, N. Dak.

Application August 4, 1941, Serial No. 405,335

5 Claims. (Cl. 146—162)

This invention relates to a potato cutting table and treater and the main object is to provide a substantial and efficient device at which a number of operators or cutters may simultaneously work slicing potatoes which are readily accessible from a bin on the cutting table. The sliced potatoes falling into a conveyor where they are conducted to a treating solution and then carried by an elevator to a container.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a side elevational view of the machine.

Fig. 2 is a longitudinal sectional view of the machine showing details of conveyor and elevator mechanisms.

Fig. 3 is a transverse sectional view taken on line 3—3, Fig. 1.

Fig. 4 is a transverse sectional view of conveyor taken on line 4—4, Fig. 1.

Fig. 5 is a plan view of the conveyor showing drive mechanism.

Fig. 6 is a plan view of the cutting table.

Referring to the drawings in detail, 10 denotes the potato cutting table which supports the conveyor 11. At one end of the table 10 there is provided an elevator 12 connected at its lower end to the conveyor 11 and supporting the power mechanism for operating the conveyor and elevator.

The table 10 is preferably made of suitable wood stock and comprises four legs 13 there being two at each end. Connecting each pair of legs is an upper board 14 the ends of which lie flush with the outer edges of the legs, and a lower board 15 the ends of which are inclined downwardly and outwardly as at 16 and which end portions extend a substantial distance beyond the legs 13. The boards 14 and 15 are disposed in superposed relation, see Fig. 3 and constitute fixed end closures for a potato bin 17. Cross-pieces 18 connect each pair of legs 13 and support a base board 19, the arrangement being such that the lower horizontal edge of the board 15 seats on said base board 19.

The bottom of the bin 17 is defined by two 55

downwardly and outwardly inclined boards 20 and 21 joined together at their inner longitudinal edges as at 22 in the vertical longitudinal center plane of the table and with their outer longitudinal edges 23 seated on the base board 19 and spaced inwardly from the longitudinal edges 24 thereof. Extending between each pair of legs 13 one on each side thereof and seated on the end extensions of the lower boards 15 are side boards 25, and disposed inwardly of said side boards 25 are stop boards 26 which are inclined downwardly and inwardly, see Fig. 3. The stop boards 26 are secured to the side boards 25 and end boards 14, 15 and have their inner longitudinal edges spaced from the surface of the bottom boards 20, 21. Preferably the inner longitudinal edge portion of each stop board 26 is cut-away as at 27 and 28. Thus, the bin 17 when filled with potatoes provides an accessible supply thereof within reach of the operators, the potatoes dropping through the openings provided between the stop boards 26 and bottom boards 21 in the manner readily apparent.

The lower ends of each pair of legs 13 are 25 braced by cross-pieces 30 which further support the conveyor 11 in the manner to be hereinafter described. Arranged between the cross-pieces 18 and 30 and secured to each pair of legs 13 are supports 31 which extend beyond the edges 24 of the base board 19 and to the ends of which are fixed the seats 32. In the form of table 10 shown each seat 32 can accommodate two operators though it is to be understood that the size of the table 10 may be varied to accommodate any desired number of operators.

The base board 19 provides two flat cutting table portions 33 between the lower edges 23 of the inclined bottom boards 20 and 21, and the edges 24 of the base board. Suitably secured to the cutting table 33 adjacent the edge thereof and centrally opposite each of the cut-away portions 28 of the stop boards 26 is a vertical knife or cutting blade 35, see Figs. 1, 3 and 6. Positioned on the underside of each of the cutting tables 33 and secured thereto are a pair of stirrups 36, one directly under each knife 35. The stirrups 36 each straddle and fixedly support the upper end of a sheet metal chute 37, the lower end of which extends into the conveyor 11 in the manner to be hereinafter described.

The conveyor 11, best shown in Figs. 2 and 3, is formed trough shaped and comprises a flat bottom 40 and parallel side walls 41 and 42, the trough being open at each end thereof. Provided in each of the side walls 41, 42 are slotted open-

ings 43 through which the lower ends of the chutes 37 project interiorly of the conveyor 11. Preferably the side walls of the chute 37 are reduced at the lower end thereof, see Fig. 3 as to provide a shoulder 38 adapted to abut the walls 41 and 42 adjacent the openings 43 therein so as to properly position the chutes 37 in the conveyor as well as to maintain the lower ends thereof in said position, the openings 43 being so dimensioned as to snugly receive the lower ends of the chutes therein so as to obviate any play therein.

The side walls 41, 42 have mounted at each end thereof opposed bearings 44 and 45 in which are rotatably mounted shafts 46 and 47, respectively. Arranged on each end of the shafts 46 and 47, adjacent the side walls 41 and 42, and fixed thereon are identical sprocket wheels 48 and 49. As will be observed, the shafts 46 and 47 are parallel and the sprocket wheels 48 and 49 on corresponding ends of the shafts 46 and 47 are in the same vertical plane. Connecting each pair of corresponding sprocket wheels is a sprocket chain 50. Viewing Figs. 2 and 3 it will be seen that the lower ends of the chutes 37 extend between the upper and lower sections of the sprocket chains with sufficient clearance therebetween. Disposed on the sprocket chains 50 in equally spaced transverse parallel relation throughout the entire extent thereof are cleats 52 of wood or any other suitable material. The cleats 52 are of a length slightly less than the inside distance between the conveyor side walls 41 and 42, and of a depth but slightly less than the distance between the lower sprocket chain section and the bottom surface of the trough, such that movement of the cleats 52 with the sprocket chains will be unimpeded.

At the forward end of the conveyor 11 and in communication therewith is the elevator 12, which is also trough shaped and comprises a bottom wall 55 and spaced parallel side walls 56. The bottom wall is continued by an end curved wall portion to define a lower end wall 51 of the trough such as to abut the bottom wall 40 of the conveyor, see Fig. 2. Preferably the end edges of the conveyor side walls 42 are inclined to abut the edges of the elevator side walls 56 as at 58. Thus, viewing Fig. 2, it will be seen that the conveyor 11 is in direct communication with the upwardly inclined elevator 12, the lower end of which by virtue of the curved end wall 51 defining a pocket or well 59 below the level of the conveyor bottom wall 40. The elevator 12 is provided at its upper end with a downwardly directed chute 60 to the mouth 61 of which may be affixed a container or bag 62 to receive therein the sliced and treated potatoes, as will be hereinafter described.

The elevator side walls 56 have mounted at each end thereof opposed bearings 65 and 66 in which are rotatably mounted upper and lower shafts 67 and 68, respectively. Arranged on each end of the shafts 67 and 68, adjacent the side walls 65 and 66, and fixed thereon are identical sprocket wheels 69 and 70. As will be observed, the shafts 67 and 68 are parallel and the sprocket wheels 69 and 70 on corresponding ends of the shafts 67 and 68 are in the same vertical plane. Connecting each pair of corresponding sprocket wheels 69 and 70 is a sprocket chain 71. Disposed on the sprocket chains 71 in equally spaced transverse parallel relation throughout the entire extent thereof are cleats 72 of wood or any other suitable material, of a length slightly less than

the inside distance between the elevator side walls 56, and of a depth but slightly less than the distance between the lower sprocket chain section and the distance between the lower sprocket chain section and the bottom wall 55 such as to provide the requisite clearance for free movement of the cleats 72 with the sprocket chains. The upper shaft 67 is located over the elevator chute 60 and remote from the upper end edge 73 of the conveyor bottom wall 55, for a purpose to be hereinafter described.

Any desired means (not shown) may be utilized for securing the cleats 52 and 72 to their respective sprocket chains. The cleats 72 are provided at their free edge portions with re-entrant openings 74 to permit the drainage therethrough of the potato treating solution 75 filling the elevator well 59.

As pointed out hereinabove, the elevator 12 is inclined forwardly and upwardly and is rigidly held in this position by means of the upper and lower pairs of braces or struts 80 and 81.

Mounted on the upper brace members 80 is an electric motor 82 on the shaft of which is fixed a small diameter pulley 83. Arranged substantially mid-way between the sprocket wheel shafts 67 and 68 is a drive shaft 84 supported in bearings 85 mounted in the elevator side walls 56 adjacent the upper edges thereof, the end portions of the shaft 84 extending outwardly beyond said side walls. On one end of the drive shaft 84 is fixedly mounted for movement therewith an inner small diameter pulley 86 and an outer large diameter pulley 87, the pulley 87 being disposed in the same vertical plane with the motor pulley 83 and connected thereto by a belt 88. On the other end of the drive shaft 84 is fixedly mounted a sprocket wheel 89. The sprocket wheel shaft 67 is provided with an extension on which is fixedly mounted a large diameter pulley 90 arranged in the same vertical plane with the pulley 86 and connected thereto by a belt 91 which moves over an idler tensioning pulley 92 mounted on the adjacent side wall 56, see Fig. 1.

The forward sprocket wheel shaft 46 of the conveyor is provided with an extension on which is fixedly mounted a sprocket wheel 93 arranged to lie in the same vertical plane with the sprocket wheel 89 on the drive shaft 84 and connected thereto by a sprocket chain 96. The sprocket chain 96 preferably operates over an idler tensioning wheel 97 carried by a suitable bracket 98 attached to the adjacent side wall 56.

Thus, with the electric motor 82 in operation, power is supplied to the conveyor sprocket wheel 48 from the drive shaft 84 by the sprocket chain drive 89, 96, 95 to move the sprocket chain 50 carrying the cleats 42 in the direction of the arrows A. At the same time power is supplied to the elevator upper sprocket wheel shaft 67 by the belt and pulley drive 86, 91, 90 to move the sprocket chain 71 carrying the cleats 72 in the direction of the arrows B.

Each cutting knife 35 located on the cutting table 33, as hereinabove pointed out is in front of a bin opening 28 and has disposed therebelow a slide chute 37. Thus the table 10 is provided with four cutting stations each seating an operator who takes potatoes from the bin 17 through the opening 28 opposite him, slices the potatoes on the knife 35 and pushes or drops the sliced potatoes onto the slide chute 37 which conducts the sliced potatoes into the conveyor 11 where the same drop on the bottom wall 40 thereof. With the machine in operation, the

cleats 52 on the moving sprocket chains 50 move the sliced potatoes forwardly where they are dripped into the well 59 containing a potato treating solution located at the bottom of the elevator 12. Here the sliced potatoes are picked up by the cleats 72 on the moving sprocket chains 71 and are carried thereby upwardly to be dumped into the elevator chute 60, see arrows C, to collect in the container 62, the treating solution in the meanwhile draining downwardly through the openings 74 of the cleats 72 and through the clearance spaces at the ends and free edge thereof.

It is thus seen that an extremely simple, efficient and satisfactory machine is provided for the purpose intended.

Having thus described the invention, what is claimed is:

1. A potato cutting and treating machine comprising a cutting table including a feed bin, spaced cutting means on said cutting table below said bin and on opposed sides thereof, a conveyor, a chute between each of said cutting means and said conveyor, a well containing a potato treating solution into which said conveyor carries the cut potatoes discharged thereinto by said chute from said cutting means, and an elevator carrying said treated cut potatoes to a discharge point for collection in a container, said conveyor and said elevator both being trough shaped, power driven endless chain means operating within each said trough, a plurality of cleats arranged in spaced fixed relation on said chain means transversely of each said trough adapted to move longitudinally of the bottoms thereof, said elevator and conveyor being in the same vertical plane and arranged in end to end angular relationship, and said well being disposed at the lower end of said elevator.

2. A potato cutting and treating machine comprising a cutting table including a feed bin, spaced cutting means on said cutting table below said bin and on opposed sides thereof, a conveyor arranged horizontally beneath said table, a chute between each of said cutting means and said conveyor, a well located at one end of said conveyor containing a potato treating solution into which said conveyor carries the cut potatoes discharged thereinto by said chute from said cutting means, and an elevator extending upwardly from said well carrying said treated cut potatoes to a discharge point for collection in a container, said conveyor and said elevator both being trough shaped, power driven endless chain means operating within each said trough, a plurality of cleats arranged in spaced fixed relation on said chain means transversely of each said trough adapted to move longitudinally of the bottoms thereof, said elevator and conveyor being in the same vertical plane and arranged in end to end angular relationship, and said well being disposed at the lower end of said elevator and below the bottom of said conveyor.

3. A potato cutting and treating machine comprising a cutting table, cutting means on said cutting table, a conveyor, a chute between said cutting means and said conveyor, a well containing a potato treating solution into which said conveyor carries the cut potatoes discharged therein by said chute from said cutting means, and an elevator carrying said treated cut potatoes to a discharge point for collection in a container, said conveyor and said elevator both being trough shaped, said well being provided at the lower end of said elevator and below the bottom

of said conveyor, said elevator and conveyor being in the same vertical plane and connected in end to end angular relationship with said conveyor horizontal, a sprocket wheel shaft transversely mounted adjacent the ends of said conveyor and elevator, a pair of sprocket wheels on each said shaft, a sprocket chain connecting corresponding sprocket wheels in said conveyor and elevator, a plurality of transverse cleats arranged in longitudinally spaced fixed relation on each said pair of sprocket wheels adapted to move across the bottoms of said conveyor and elevator, an electric motor, a drive shaft on said elevator, a speed reducing belt drive between said motor and drive shaft, a speed reducing belt drive between said drive shaft and the upper sprocket wheel shaft of said elevator, and a sprocket chain drive between said drive shaft and the sprocket shaft of said conveyor adjacent said elevator.

4. A potato cutting and treating machine comprising a cutting table, cutting means on said cutting table, a conveyor, a chute between said cutting means and said conveyor, a well containing a potato treating solution into which said conveyor carries the cut potatoes discharged thereinto by said chute from said cutting means, and an elevator carrying said treated cut potatoes to a discharge point for collection in a container, said conveyor and said elevator both being trough shaped, said well being provided at the lower end of said elevator and below the bottom of said conveyor, said elevator and conveyor being in the same vertical plane and connected in end to end angular relationship with said conveyor horizontal, a sprocket wheel shaft transversely mounted adjacent the ends of said conveyor and elevator, the lower elevator sprocket wheel shaft lying within said well, a pair of sprocket wheels on each said shaft, a sprocket chain connecting corresponding sprocket wheels in said conveyor and elevator, a plurality of transverse cleats arranged in longitudinally spaced fixed relation on each said pair of sprocket wheels adapted to move across the bottoms of said conveyor and elevator, an electric motor, a drive shaft on said elevator, a speed reducing belt drive between said motor and drive shaft, a speed reducing belt between said drive shaft and the upper sprocket wheel shaft of said elevator, and a sprocket chain drive between said drive shaft and the sprocket shaft of said conveyor adjacent said elevator, said belt drives being arranged on one side of said elevator and said sprocket chain drive being arranged on the other side of said elevator, the ratio of said drives being such that the elevator sprocket chains move at a slower rate than the conveyor sprocket chains.

5. A potato cutting and treating machine comprising a cutting table, cutting means on said cutting table, a conveyor, a chute between said cutting means and said conveyor, a well containing a potato treating solution into which said conveyor carries the cut potatoes discharged thereinto by said chute from said cutting means, and an elevator carrying said treated cut potatoes to a discharge point for collection in a container, said conveyor and said elevator both being trough shaped, said well being provided at the lower end of said elevator and below the bottom of said conveyor, said elevator and conveyor being in the same vertical plane and connected in end to end angular relationship with said conveyor horizontal, a sprocket wheel shaft trans-

versely mounted adjacent the ends of said conveyor and elevator, a pair of sprocket wheels on each said shaft, a sprocket chain connecting corresponding sprocket wheels in said conveyor and elevator, a plurality of transverse cleats arranged in longitudinally spaced fixed relation on each said pair of sprocket wheels adapted to move across the bottoms of said conveyor and elevator, an electric motor, a drive shaft on said elevator, a speed reducing belt drive between said motor and drive shaft, a speed reducing belt drive between said drive shaft and the upper sprocket wheel shaft of said elevator, and a sprocket chain

drive between said drive shaft and the sprocket shaft of said conveyor adjacent said elevator, said cleats fixed to the pair of elevator sprocket chains being provided at their free edges with transversely spaced drain openings, a depending chute fixed to the upper end of said elevator, means to mount a container on the terminal end of said chute, said upper elevator sprocket wheel shaft being disposed over the chute opening and beyond the upper terminal end of said elevator bottom.

ROY A. HURTT.
